(57) **CLAIM**

The ornamental design for a nozzle for ink bottle for refilling printer cartridges, as shown and described.

DESCRIPTION

FIG. 1: Front

FIG. 2: Back

FIG. 3: Top

FIG. 4: Bottom

FIG. 5: Left

FIG. 6: Right

FIG. 7: Perspective

FIG. 8: Perspective; and,

FIG. 9: Cross-sectional view of FIG. 3 along center line A-A.

1 Claim, 9 Drawing Sheets

FIG. 1

FIG. 2

FIG. 3

FIG. 4

FIG. 5

FIG. 6

FIG. 7

FIG. 8

FIG. 9
